United States Patent Office

Des. 185,497
Patented June 16, 1959

185,497

TRUNDLE TOY

John M. Harriman, Morton, Pa., assignor to James Industries, Inc., Paoli, Pa., a corporation of Pennsylvania

Application February 11, 1958, Serial No. 49,599

Term of patent 14 years

(Cl. D34—15)

FIG. 1.

FIG.2.

FIG.3.

Fig. 1 is a perspective view of a trundle toy, showing my new design;

Fig. 2 is a side elevational view thereof; and
Fig. 3 is a rear elevational view thereof.

I claim:

The ornamental design for a trundle toy, as shown.
